CLAIM

The ornamental design for a faucet handle, as shown and described.

DESCRIPTION

FIG. 1 is a front perspective view of a first embodiment of a faucet handle, showing the new design;

FIG. 2 is a front view of the first embodiment of the faucet handle;

FIG. 3 is a rear view of the first embodiment of the faucet handle;

FIG. 4 is a side view of the first embodiment of the faucet handle;

FIG. 5 is another side view of the first embodiment of the faucet handle;

FIG. 6 is a top view of the first embodiment of the faucet handle; and,

FIG. 7 is a bottom view of the first embodiment of the faucet handle.

The broken lines showing various elements of the faucet handle are included for the purpose of illustrating non-claimed subject matter and form no part of the claimed design.
